UNITED STATES PATENT OFFICE

114,637

DESIGN FOR A DISPENSING CABINET

Norman E. Heil, Ridgewood, and John O. Camp,
Glen Rock, N. J.

Application September 26, 1938, Serial No. 80,106

Term of patent 14 years

To all whom it may concern:

Be it known that we, Norman E. Heil and John O. Camp, citizens of the United States, residing at Ridgewood and Glen Rock, respectively, county of Bergen, State of New Jersey, have invented a new, original, and ornamental Design for Dispensing Cabinets, of which the following is a specification, reference being had to the accompanying drawing, forming part thereof.

We claim:

The ornamental design for a dispensing cabinet, as shown.

NORMAN E. HEIL.
JOHN O. CAMP.
